UNITED STATES PATENT OFFICE.

MARTIN H. MANSFIELD, OF ASHLAND, OHIO.

IMPROVEMENT IN CLOVER-MACHINES.

Specification forming part of Letters Patent No. 31,764, dated March 25, 1862.

To all whom it may concern:

Be it known that I, MARTIN H. MANSFIELD, of Ashland, in the county of Ashland and State of Ohio, have invented new and useful Improvements in Clover-Hulling Machines, (the same being an improvement on a similar machine for which a patent was granted to me under date of June 6, 1846;) and I do hereby declare that the following is a full and complete description of the construction and operation of the same, reference being had to the accompanying drawings, making part of this specification, in which—

Figure 1 is a side view. Fig. 2 is a view of opposite side of that shown in Fig. 1. Fig. 3 is a top view. Fig. 4 is a vertical section in the direction of the line $x'x'$ in Fig. 3. Fig. 5 is an enlarged view of one of the teeth. Fig. 6 is the cylinder detached, and Fig. 7 a section of the concave detached.

Like letters denote like parts in the several views.

The nature of my invention relates to the following-named parts: first, to the herein-described construction of the cylinder-teeth, so that while one part is being worn the other part is being sharpened, the teeth being made double; second, to such an arrangement of the teeth upon the cylinder that the teeth themselves can be reversed, or by reversing the cylinder itself the teeth will thereby be reversed in their action; third, suspending the cylinder by means of self-adjustable bearings at the extreme ends of the shaft in such a manner that the shaft and boxes will always be in line with each other; fourth, in the introduction of a secondary hopper and feeding-reel, by means of which the machine is uniformly fed, and at the same time stones and other hard substances separated from the clover-heads and prevented from entering into the machine.

The general form and structure of the machine are shown in Figs. 1, 2, and 3.

A, Figs. 3 and 4, is a wire-cloth screen which separates the coarser chaff and stems from the separated seed.

B is a fan-wheel, put in motion by means of a belt, B', for separating the lighter chaff and dust from the seed.

C is the cylinder armed with the double reversible teeth F, the shaft of which cylinder

is hung in self-adjusting boxes D D, and having the driving-pulley E inside of the bearings. These boxes are solid pipe-boxes, and are supported in the center of a ring, D', by screw-points D², upon which the box can articulate in a horizontal plane. The ring D' is supported on screw-points passing through the bearings D³, which allows an adjustment of the box D in a direction at right angles to that above described, thus forming for the support of the box a universal joint. By loosening one of the screws D² on each side of the machine, and removing the upper part of the concave, as hereinafter described, the cylinder can be reversed in its position, thus bringing into action either section of the teeth at pleasure.

The cylinder C is armed with peculiarly-shaped teeth F, Figs. 4, 5, and 6. These teeth are double-wedge shaped—that is, they are thickest in the middle and taper toward a point at both ends—and have angular serrated sides, as seen at G, Fig. 5.

I, Fig. 5, shows the thickest part of the tooth, and I' I² the thinner ends. These teeth are secured in regular order to the surface of the cylinder in any convenient manner.

The teeth of the concave K, Fig. 7, are wedge-shaped, and have also angular serrated faces, the thinner end being presented to the direct motion of the cylinder; and these teeth are so placed that the teeth attached to the cylinder will pass between them in the direction of the arrow in Fig. 7, the thin ends of the cylinder-teeth entering between the thin ends of the teeth of the concave, the space between them when they first enter being about one inch, but as the cylinder rotates the space between the thicker ends being contracted to about one-quarter of an inch, and in this way the clover-heads or other substance is subjected to a sufficient amount of friction to separate the seeds without injury to the latter.

The concave K' K² is made in two parts. The upper part, K', is so connected with the upper part of the frame-work as to be detachable from the lower section, K², thus making the concave in two primary sections, so that the upper one can be easily removed for the purpose of getting at the cylinder in order to reverse its position or change the teeth. The concave is also divided into secondary sections or lugs, as seen in Fig. 7, which sections

are so made as to slide in and out in a groove in the sides of the frame at the ends of the concave or cylinder-case. At each end of the lug is a tenon which fits into a corresponding groove at the ends of the concave or cylinder-case.

When the machine is at work, the cylinder C moves in the direction of the arrows in Fig. 4, and the wear will be on the serrations of the tooth from I' to I², and the tooth from I' to I¹ will be worn in the same direction—that is, the points L will be worn off in the direction shown in Fig. 5 in the enlarged section—thus reducing the angles to a more obtuse form, and thus lessening their action upon the material acted upon; but by reversing the teeth, which may be done either by turning the teeth from I' to I², which may be accomplished either by reversing the teeth in the cylinder or by reversing the position of the cylinder, (the driving-pulley E fitting either end of the shaft,) the sharper angles L are thus brought into action, and thus by the very friction of the teeth upon the material acted upon a self-sharpening process is accomplished.

No difficulty will be experienced in bringing the shaft of the cylinder C into line with the boxes, for these, as before described, are self-adjusting. These changes in the position of the cylinder may continue to be made as often as the teeth become worn until the angles are nearly worn off, thus making the machine much more durable and effective than it would be in the old way, as described in my former patent.

M, Figs. 1, 2, 3, and 4, represents the primary hopper. To this is attached a second-

ary hopper, N, in which is placed a revolving feeder, O, having suitable bearings at the ends of its shaft. This revolving feeder is armed with radial teeth which sweep around in the concavity P in the direction indicated by the arrow. The object of this arrangement is to cause a regular and uniform feed of the un-hulled clover to the cylinder, for the material being light is liable to be drawn into the cylinder-concave in masses, thus clogging the machine. In my former machine it required the constant attention of one person to regulate the feed, which extra labor is wholly saved by the use of my present device for feeding; and, further, by means of this revolving feeder O the regularity of feed is greater than can be accomplished by hand; and still another advantage of very great importance is gained by use of the revolving feeder.

Stones and other hard substances, which would otherwise pass into the machine and become wedged between the teeth of the concave and the teeth of the cylinder C, are collected in the concavity P, from whence they can from time to time be removed by the hand of the operator.

What I claim as my improvement, and desire to secure by Letters Patent, is—

The reversible cylinder C, in combination with the self-adjustable box D, and primary and secondary hoppers M' N, with revolving feeder O, as and for the purposes set forth.

M. H. MANSFIELD.
